(57) **CLAIM**

The ornamental design for an LED lamp, as shown and described.

DESCRIPTION

This application is related to U.S. application Ser. No. 29/360,121, filed Apr. 20, 2010, the entire contents of which is incorporated by reference herein.

FIG. 1 is a top front perspective view of an LED lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom front perspective view thereof;

FIG. 9 is a first exploded view thereof; and,

FIG. 10 is a second exploded view thereof.

The broken diagonal lines in FIG. 8 mark light emitting parts and form no part of the design.

The broken line showing of FIGS. 1-10 is for the purpose of illustrating environmental structure and forms no part of the claimed design.
